(57) **CLAIM**

The ornamental design for a pump head cover for a peristaltic pump as shown and described.

DESCRIPTION

FIG. 1 is a front top perspective view of a pump cover for a peristaltic pump according to an embodiment of the invention.

FIG. 2 is a rear bottom perspective view of the pump cover of FIG. 1.

FIG. 3 is a front bottom perspective view of the pump cover of FIG. 1.

FIG. 4 is a front view of the pump cover of FIG. 1.

FIG. 5 is a rear view of the pump cover of FIG. 1.

FIG. 6 is a top view of the pump cover of FIG. 1.

FIG. 7 is a bottom view of the pump cover of FIG. 1.

FIG. 8 is a left side view of the pump cover of FIG. 1; and, FIG. 9 is a right side view of the pump cover of FIG. 1. The portions of the drawings appearing in broken lines are for environment only and do not form a part of the claimed design.
